DESIGN FOR A TOY GLIDER

Harold E. B. Gary, Aurora, Ill.

Application July 11, 1936, Serial No. 63,779

Term of patent 14 years

To all whom it may concern:

Be it known that I, Harold E. B. Gary, a citizen of the United States, residing at Aurora, in the county of Kane and State of Illinois, have invented a new, original, and ornamental Design for Toy Glider, of which the following is a specification, reference being had to the accompanying drawing, forming a part thereof:

Figure 1 is a perspective view of a toy glider showing my new design;

Figure 2 is a side elevational view of the toy glider illustrated in Figure 1;

Figure 3 is a top plan view of the toy glider illustrated in Figure 1, and

Figure 4 is a front elevational view of the same.

I claim:

The ornamental design for a toy glider as shown.

HAROLD E. B. GARY.
